UNITED STATES PATENT OFFICE.

JOHN A. BLAKE, OF WATERTOWN, NEW YORK, ASSIGNOR TO THE PRENTISS VISE COMPANY, OF NEW YORK, N. Y.

VICE.

SPECIFICATION forming part of Letters Patent No. 396,066, dated January 15, 1889.

Application filed August 16, 1886. Serial No. 210,990. (No model.)

To all whom it may concern:

Be it known that I, JOHN A. BLAKE, of Watertown, county of Jefferson, and State of New York, have invented certain new and useful Improvements in Bench-Vises, of which the following is a full, clear, and exact description, reference being had to the accompanying drawings, and to the letters of reference marked thereon.

10 My invention has relation to that class of devices known as "bench-vises" and ordinarily used by metal-workers and others for clamping and holding articles in position to be worked upon.

15 My invention has for its object the provision of simple, cheap, durable, and effective means for permitting one of the vise jaws or heads to be rapidly adjusted with respect to the other independently of the ordinary adjustment or clamping screw without in any way interfering with the effective operation of the said screw. To accomplish this my improvements involve certain new and useful peculiarities of construction, relative arrangements or combinations of parts, and principles of operation, all of which will be herein-after first fully described, and then pointed out in the claims.

20

25

In the accompanying drawings, forming part of this specification, Figure 1 is a longitudinal section and elevation of my improved vise, showing the two half-nuts in engagement with the clamping-screw and the vise as resting upon the detachable swivel-base. Fig. 2 is a similar view showing the two half-nuts out of engagement with the clamping-screw, (so that the head may be rapidly moved in either direction,) omitting the swivel-base. Fig. 3 is a plan, and Fig. 4 a side elevation, of the base-piece detached. Fig. 5 is a cross-section and partial elevation upon a plane passing through the two half-nuts and through the wedge-blocks by which they are operated, the nuts being in engagement with the clamping-screw, as in Fig. 1. Fig. 6 is a perspective view of the half-nuts detached from the screw and from each other, and Fig. 7 is a similar view showing the wedge-bar and operating-wedges as in Figs. 1 and 2. Fig. 8 is a cross-section showing the upper nut ar-

ranged to hook over or project beyond the lower nut.

In all the figures like letters of reference, wherever they occur, indicate corresponding parts.

55 Provision has heretofore been made for the rapid adjustment of one of the vise-heads, and vises admitting of such adjustment are known as "rapid-transit" vises. Single half-nuts have heretofore been arranged to be thrown in or out of engagement with the clamping-screw, and half-nuts hinged together within the structure and moving in arcs of circles have also been employed. These former constructions have failed to 60 clamp and release the screw with that certainty, accuracy, and solidity which is necessary, especially in vises required for heavy work or where extreme pressure is required in clamping articles between the jaws, so that 65 while they may add to the rapidity with which the vise may be set they detract from its efficiency as a means for clamping and sustaining the work. I therefore make the two half-nuts so that together they will bear upon the 70 screw as one whole nut, and arrange them so that they will move toward or from the screw simultaneously in straight lines and in opposite directions, as will herein-after appear.

75

80

In the drawings, A represents the stationary head, and B the adjustable head, the latter being mounted upon the sliding bar C, within which the clamping-screw D is mounted and arranged to turn.

85

90

E E' are the two half-nuts arranged to embrace the screw D, each half-nut being mounted upon a stem or shank, as e e', fitted to move freely in a suitable recess provided for the shanks in the base part of the vise. The means or mechanical device employed for moving the half-nuts operates upon the shanks. In Figs. 1, 2, 5, and 6 the half-nuts are moved by wedges. The shanks are provided with interior inclined channels or 95 grooves, as at a a', tending in opposite directions—that is, one up and one down when viewed from either side.

95

100

F is a movable bar carrying the inclined pieces or wedges b b', which wedges enter the

inclined channels a a' . The bar F projects through to the front of the vise, where it is within convenient reach of the operator, being provided with any suitable head, as c, and supplied with a returning spring of any form, as d, and a notch or catch, as at f, by which it is held against the action of the spring, as in Fig. 2.

The half-nuts being in the position shown in Fig. 1, they embrace the screw firmly, accurately, and completely, and the screw may be employed to move the vise-head B the same as in any ordinary vise. To release the screw so that the head B may be advanced or retracted without interference or without the necessity of turning the screw, the bar F is drawn out, as in Fig. 2, the inclines or wedges b b' moving in the channels a a' , causing the half-nut E to move off the screw in one direction and the half-nut E' to move in the opposite direction, thus entirely disengaging the screw. Then the head B may be moved at pleasure.

The bar F may be locked in position by bringing its notch into engagement with the wall of the orifice through which it slides. Upon releasing bar F the spring d automatically returns it to its original position, the wedges or inclines forcing the half-nuts back to their bearings upon the screw. If the threads upon the half-nuts do not immediately enter the spaces between those upon the screw, a very slight turn of the latter will permit them to do so. The half-nuts when brought together operate precisely as a whole nut and with equal holding effect.

The half-nuts may be formed, as indicated in Fig. 5, so that the margins on the open side may abut against each other, or preferably as in Fig. 8, so that one-half nut passes beyond the other in the form of a hook. This latter construction affords a guide above or beyond that afforded by the slot in which the shanks move, and also affords protection against the admission of clippings or other matter between the half-nuts.

G is the bed-plate of a swivel-base which may be used. H are bolts passing through

holes in the vise and through corresponding perforations I I in the bed-plate. A bolt, K, 50 projects through the bed-plate and receives a hand-nut, L, and washer M. The nose N upon the vise enters a recess, N'.

Having now fully described my invention, what I claim as new, and desire to secure by Letters Patent, is—

1. In a vise, and in combination with the screw thereof, a divided nut consisting of two vertically-moving sections, each having a rigid part extending below the screw, and an opener, 60 as the bar F, working in recesses in the sections, substantially as described.

2. In a vise, the two half-nuts arranged to move in parallel lines and provided with the shanks having oppositely-inclined channels, 65 the sliding bar carrying the wedges or inclines, and the clamping-screw, combined and arranged for operation substantially as shown and described.

3. In a vise, the two half-nuts arranged to move in parallel lines and provided with the channeled shanks, the sliding bar carrying the two wedges for engaging with the shanks and forcing the half-nuts to move simultaneously in opposite directions, a returning spring applied in connection with said bar, and the clamping-screw mounted in the sliding vise-bar, combined and arranged substantially as shown and described.

4. In a vise, and in combination with the screw thereof, a divided nut having one section constructed to rise and the other to fall, and each section having an inclined groove, the two grooves running in opposite directions and their central lines crossing each other, a 85 slide working between the sections, provided with studs working in said grooves, whereby the one section is raised and the other lowered, substantially as described.

In testimony that I claim the foregoing I 90 have hereunto set my hand in the presence of two witnesses.

JOHN A. BLAKE.
